US00D715990S

(12) **United States Design Patent**
Zhang et al.

(10) **Patent No.:** **US D715,990 S**
(45) **Date of Patent:** **** Oct. 21, 2014**

(54) **LENS**

(71) **Applicant:** **Wan-Jiong Lin**, Ningbo (CN)

(72) **Inventors:** **Fa-Wei Zhang**, Ningbo (CN); **Le Xu**, Ningbo (CN); **Wan-Jiong Lin**, Ningbo (CN)

(73) **Assignees:** **Wan-Jiong Lin**, Ningbo (CN); **Ningbo Self Electronics Co., Ltd.**, Ningbo (CN); **Self Electronics USA Corporation**, Norcross, GA (US)

(**) **Term:** **14 Years**

(21) **Appl. No.:** **29/448,181**

(22) **Filed:** **Mar. 11, 2013**

(51) **LOC (10) Cl.** **26-99**

(52) **U.S. Cl.**
